UNITED STATES PATENT OFFICE.

RICHARD C. SPECHT AND AXEL S. NIELSEN, OF SAN FRANCISCO, CALIFORNIA.

SUPPORT FOR A PRESS.

1,172,400.

Specification of Letters Patent. Patented Feb. 22, 1916.

Application filed January 8, 1914. Serial No. 810,994.

To all whom it may concern:

Be it known that we, RICHARD C. SPECHT and AXEL S. NIELSEN, citizens of the United States, residing at San Francisco, in the 5 county of San Francisco and State of California, have invented a new and useful Support for a Press, of which the following is a specification in such full and clear terms as will enable those skilled in the art to construct and use the same.

This invention relates to a machine for the purpose of cutting meat, making noodles or macaroni, stuffing sausages or pressing fruit juices, the several purposes being accomplished by the mere interchange of several different types of dies.

An object of the invention is to provide means whereby the materials being operated upon will be held under compression 20 so that they will be forced through the dies for a short time after the pressure screw has ceased to move, thereby enabling the person using the machine to cut off the string of macaroni issuing therefrom, or to 25 operate the meat cutting knife without continuously forcing the screw down.

Another object of the invention is to provide means whereby the machine may be supported in any one of several convenient 30 positions for operation.

Other objects of the invention will appear as the description proceeds.

An embodiment of the invention is shown in the drawing in which the same reference 35 numeral is applied to the same portion throughout, but we are aware that there are many modifications thereof.

Figure 1 is a longitudinal sectional view through the feed cylinder, Fig. 2 is a view 40 of the lower portion of the clamp used to support the machine, said clamp being an extension of the standard shown at the bottom of Fig. 1, Fig. 3 is a side elevation of one of the stay rods illustrating the manner 45 of assembling the several parts of the machine thereon, Fig. 4 is a plan view of the machine as it appears assembled on the corner of a table, Fig. 5 is a plan view of the supporting bracket and the lower portion 50 of the hopper, all of the upper parts being removed for purposes of illustration, Fig. 6 is a plan view of one of the stay rods and a portion of one of the hooks attached to the hopper and die plate showing the 55 manner of assembling the machine, Fig. 7 is a plan view of one of the stay rods and

one of the hooks showing the position thereof after the several parts have been assembled upon the stay rod, Fig. 8 is a plan view of one of the stay rods and one 60 of the hooks on the opposite side of the machine from the hooks shown in Figs. 6 and 7, Fig. 9 is a plan view of the screw used for forcing the piston into the machine and showing the feather way therein to prevent 65 it from turning, Fig. 10 is a view of the discharge end of the machine and the supporting clamp as it appears when the machine is to be used as a meat cutter with the feeding cylinder turned to the horizontal 70 position, Fig. 11 is a view of the upper end of the supporting standard, Fig. 12 is a view of the meat cutting die and knife, Fig. 13 is a sectional view of the meat cutting die showing the knife in contact therewith, 75 Fig. 14 is a side elevation partly broken away for purposes of illustration of a die used when it is desired to stuff sausages with the machine, Fig. 15 is an end view of the cylinder of the machine showing the 80 supporting standard therefor broken away for purposes of illustration, Fig. 16 is a view of the macaroni or noodle making die, a portion of one of the dies being broken away for the purpose of showing the outer 85 die, and Fig. 17 is a sectional view through both of the macaroni dies.

The numeral 1 indicates a standard or supporting post which carries the machine. This post has a transverse opening therein 90 at the upper end for the insertion of a stud 2 on the yoke 3, which directly carries the machine. At the lower end the post is provided with a clamp 4 for securing the post to a table or other support. This clamp 95 is tightened in place by means of the screw 5, which has the pivoted handle 6 connected therewith.

In order to hold the machine in either the horizontal or vertical position, the stud 2 has a pin 7 passing therethrough, which pin 100 may be seated in any one of four notches in the upper end of the post, thereby holding the machine in whichever position it is desired to place it in and when said pin is seated a screw 8 is passed down into a groove 9 of the stud 2 to hold the stud firmly in place.

The ends of the yoke are enlarged as indicated at 10 and 11 to receive the long stay 110 bolts 12 and 13, said bolts being secured to the yoke by means of a pin passing through

each bolt as indicated in dotted lines in Fig. 10 at 14 and 15. The bolt 12 has notches 16 and 17 formed therein for the purpose of enabling the die holder 18 and cylindrical shell 19 to be assembled in place.

It will be observed that the die holder has a hook 20 at one side and a reversely placed hook 21 at the other side, said hook being inserted on the stay rod 12 when in the position shown in Fig. 6, after which it is rotated to the position shown in Fig. 7 with the hook 21 in contact with the stay bolt 13, whereupon the screw 22 is turned up against the bolt 13 to secure the die holder in place.

The cylindrical shell 19 has two hooks 23 and 24 which are so positioned as to meet the notches 16 and 17 in the bolt 12 and which has a hook 25 which is intended to contact with the bolt 13, said hook having a thumb screw 26 similar to the thumb screw 22 to hold the hopper firmly in place. The hopper is assembled upon the stay rod as indicated in Fig. 6, whereupon it is turned as indicated in Fig. 7 with the other hook carried thereby which contacts with the rod 13, whereupon one end of the hopper passes down into the die holder. However, before the hopper is placed in the die holder one of the desired dies must be placed in said die holder, whichever die it is desired to use, whether a plain die 27 having a plurality of holes therein as shown in Fig. 5, a meat cutting die 28, sausage stuffing funnel 29 or the macaroni dies 30 and 31. Each of the dies is provided with a pin 32 to prevent them from turning with respect to the die holder.

The noodle making die 27 comprises a flat plate having a plurality of holes therein. The meat cutting die comprises a flat plate 28 having a boss 33 projecting therefrom, said boss having a hole therein to afford a bearing for the pin 34. This pin supports and rotates the knife 35, said knife having cutting edges on each side thereof and being concaved and having its concaved side against the die 28 to afford it a good cutting contact with said die.

The pin 34 is threaded at its outer end as indicated at 36 and has a crank 37 applied thereto, said crank being held in place by means of the wing nut 38. The sausage stuffing funnel comprises a funnel 29 having a flange 39 and a spout 40 which may be of such length as is deemed desirable. The macaroni die is made up of two parts, one a plate 31 having a flange 41 with round holes therein, the other a plate 30 with a plurality of slots therein and carrying a series of pins 42 which project into the holes of the plate 31.

It will be observed that the plate 31 carries a series of lugs 43 between which lugs the radial extending members of the plate 30 lie, while nearer the center the plate 31

has a plurality of lugs 44, upon the top of which lugs the plate 30 lies and which lugs serve to hold the two plates the proper distance apart to produce the macaroni tubes when the material is pressed through the two plates.

The cylindrical shell is held down against the die holder by means of two thumb nuts 51 and 52. Pressure is exercised upon the materials which are placed in the cylindrical shell by means of the piston 50. This piston has a rod 53 connected therewith which rod is turned smaller at 54 to receive a nut 55, and has two shoulders at 54' and slidable on it is the pressure screw 56. The pressure screw 56 bears upon a heavy spring 57 which in turn bears upon the piston, the object of said spring being to force the material out of the hopper even when the forward movement of the screw has ceased, thereby enabling the person using the same to cut off a string of material several times during such motion of the piston. In order not to strain the spring the screw is provided with a cap 58. This cap surrounds the small part of the piston rod at 54 and it has a set screw 59 to hold it in a given position. When the pressure comes on the piston if a great enough pressure is applied, said cap will contact with the shoulder on the piston and for that reason cannot compress the spring 57 more than an amount which will not injure it, while the nut 55 will cause said screw to lift the piston when so desired.

The screw passes through a revoluble block 60 in a transverse support 61. This support is held in a given position by means of suitable nuts 62, 63, 64, 65, 66 and 67 and it affords a bearing at 68 for a shaft 69. The screw block is threaded at its upper end and carries a bevel wheel 70, which bevel wheel is in mesh with a pinion 71 on the shaft 69, the latter shaft being rotated by means of the crank 72. A screw 70' is used to prevent the bevel wheel 70 from rotating with respect to the flanged screw block 60. In order to prevent the screw from rotating with the block 60 instead of being moved longitudinally therethrough, a plate 73 is secured to the underside of the cross piece 61, said plate having a feather 74 which projects into a feather-way in the screw 56.

In operation the nut 51 is released, the thumb nuts holding the cylindrical shell and die plate in place are released, the piston is withdrawn from the cylindrical shell, whereupon the hopper may be swung out into a convenient position to be charged, after which it may be returned to the position shown in Fig. 1 and the piston forced thereinto to press the materials against whichever die it may be desired to use. If the meat cutting knife is to be used its

knife will be rotated as the pressure is put upon the piston the meat thereby being cut into small bits, which in turn are forced through the holes in the die.

5. It will also be observed that an object of the invention is to produce a machine which can be easily and quickly disassembled for shipment whenever so desired.

It will be noted that cap 58 carried by 10 the feed screw will prevent the piston from rotating as well as prevent the screw from bearing upon the spring too heavily. Attention is also called to the fact that the knife used for meat cutting purposes will 15 cut in both directions, thus doubling the life of the die and the knife. When it is desired to change the dies all that is necessary is to raise the hopper out of the die holder, whereupon the desired die may be inserted 20 in place after removing the one that has been in use.

Having thus described our invention what we claim as new and desire to secure by Letters Patent of the United States, is as follows, modifications within the scope of the 25 claims being expressly reserved:

1. In a device of the class described, the combination of a support, a Y shaped yoke carried thereby, a pair of rods carried by

the yoke, a cylindrical shell having a number of open ears to secure it in place on said rods, a die holding ring having open ears to secure it to the rods under the cylindrical shell and within which said cylindrical shell fits, and a cross bar on the upper 35 ends of the rods and extending across the top of the cylindrical shell.

2. In a device of the class described, the combination of a support, a Y shaped yoke pivotally mounted therein, a pair of threaded rods rigidly supported by said yoke, a die holding ring having open ears to secure it to said rods, a cylindrical shell having a plurality of open ears to secure it to the rods and seated in the die holder, a cross 40 bar rigidly connected with the threaded ends of the rods and extending across the top of the cylindrical shell, and means to rigidly secure the shell to the rods.

In testimony whereof we have hereunto 45 set our hands this 27th day of December A. D. 1913, in the presence of the two subscribed witnesses.
